John Morrissey

UNITED STATES PATENT OFFICE.

ALPHONSE J. DE LEERS, OF MARINETTE, WISCONSIN.

COVER-FILLING MACHINE.

Application filed June 25, 1923. Serial No. 647,664.

To all whom it may concern:

Be it known that I, ALPHONSE J. DE LEERS, a citizen of the United States, and resident of Marinette, in the county of Marinette and State of Wisconsin, have invented certain new and useful Improvements in Cover-Filling Machines; and I do hereby declare that the following is a full, clear, and exact description thereof.

10 This invention relates to cover filling machines and although it is particularly adapted for filling match box covers, it is also adapted for other widely different uses.

15 In order to simplify the drawings and description of this application, the machine will be described as adapted for the filling of match box covers, but it is to be distinctly understood that the invention is not limited to this sphere of usefulness, but is to be limited only as claimed.

20 Heretofore it has been the practice to insert the filled match box within the cover by hand. It has been found that this process is slow and needlessly adds to the cost 25 of the finished article.

25 Objects of this invention are to provide a machine for filling covers, which will project the fillers into the covers in an automatic, smooth and rapid manner, which 30 will accurately center each cover prior to the filling operation thereby avoiding jamming or damage to the machine, and which 35 will advance the covers in a step by step manner so that the entire operation is wholly automatic, smooth and rapid, and accurate functioning of the machine is secured.

40 Further objects are to provide a machine for filling match box covers, which will handle the boxes although the matches may be 45 piled slightly above the upper surface of the box, which will hold the matches within the box, which will compress the matches and force them into the box prior to the sliding of the box into the cover, and which 50 will automatically accurately guide the filled boxes into the covers.

55 Further objects are to provide a machine for filling match box covers in which the various portions of the mechanism are positively operatively connected and are so timed that a cover is advanced to the correct position, is thereafter, accurately cen-

tered and a filled box is inserted into the cover while it is so centered.

55 An embodiment of the invention is shown in the accompanying drawings, in which:

Figure 1 is plan view of the machine with portions broken away to more clearly show the construction.

60 Figure 2 is a longitudinal sectional view through the machine.

Figure 3 is a sectional view on the line 3—3 of Figure 2.

65 Figure 4 is a detail of the right hand portion of the mechanism illustrated in Figure 2 showing the mechanism in a different position, or at a different period in its cycle of operation.

The machine comprises a bed plate 1 which is equipped with an entrance trough 70 or feed trough 2 for the filled boxes and is provided with a guide way 3 for the covers. An upwardly extending open chute 4 is mounted above the guide way 3 and is adapted to receive the empty covers 5, such 75 covers being supplied the chute in any suitable manner. This particular plate may, of course, be carried upon any desired type of supports, and may take other forms from the exact forms shown. Three short vertical shafts 6, 7 and 8 are carried in suitable bearings formed integrally with the bed plate and project upwardly through such plate. The shaft 6 is provided with a bevel gear 9 which meshes with a bevel gear 10 80 carried by the transverse driving shaft 11, such shaft being provided with a pulley 12 or other suitable driving means. The shafts 6, 7 and 8 are provided, respectively, with sprocket wheels 13, 14 and 15 which, as may 85 be seen from Figure 1, are connected by a sprocket chain 16, so that all of the shafts move in unison and at exactly the same speed as the sprocket wheels are all of the same size. The bed plate carries a forward 90 guide way 17 and a rear guide way 18 within which is slidably positioned the feed plunger 19 for the boxes. Reciprocatory motion is imparted to this plunger by means 95 of a crank arm 20 rigidly attached to the upper end of the shaft 6 and provided with an upwardly projecting pin 21 adapted to slide in a slot 22 formed in the cross head 23, such cross head being rigidly carried

100

by the plunger 19. The guide way 17 is in effect a sleeve, as may be seen from Figures 2, 3, and 4 and is itself adapted for reciprocatory motion to a limited extent upon the bed plate 1. It is carried by the guides 24 (see Figure 3) and is provided with a transverse slot 25. A pin 26 fits within the slot and is carried eccentrically upon a disk 27 rigidly attached to the shaft 7. Thus when the shaft 7 rotates, the sleeve will be given a reciprocatory motion in and out towards the chute 4. This sleeve is provided with a lateral aperture 28 through which the filled boxes 29 (see Figure 3) may be fed in any suitable manner. The plunger 19 is provided with a forwardly projecting portion 30 which may form an integral continuation of the rear portion and of a lesser thickness than the body portion. This portion 30 is supplemented by a portion 31 of approximately similar extent and pivotally mounted, as indicated at 32 (see Figures 2 and 4) to the body portion. A spring 33 urges the pivoted arm 31 upwardly and an anti-friction roller 34, carried by such upper arm relieves the device of excessive friction as such roller travels upon the upper side of the sleeve 18 thus materially reducing friction.

It is to be noted from Figures 2 and 4 that the inner portion of the sleeve 17 is tapered being largest approximately adjacent the aperture 28 through which the filled boxes are passed. The upper side 35 of this central opening tapers downwardly towards the forward end of the plunger, as may be seen from Figures 2 and 4. A convenient way of forming this sleeve is also to taper the outer forward surfaces thereof, as may be seen from Figures 2 and 4. A plurality of resilient fingers 36 are secured to the tapered sides and converge and approach each other under normal conditions more closely than the cross section area of a box 29 of matches. This tapered nose of the plunger formed by the members 36 is adapted to be projected into one of the covers 5 and to accurately center the cover (as shown in Figure 4) prior to the feeding of the box into the cover. A feed plunger 37 for the covers 5 is provided and is guided in a rear extension of the guide-way 3, as may be seen from Figures 1 and 3. This feed plunger is provided with a transverse slot 38 upon its under side which receives a pin 39 eccentrically carried by a disk 40. The disk is rigidly attached to the shaft 8 and consequently, as the shaft rotates the reciprocatory member 37 will push the box covers outwardly in a step by step manner—the stroke of such plunger 37 being approximately equal to the width of the match box cover.

A convenient way of feeding the filled boxes 29 into the sleeve or guide 17 is illus-

trated in Figure 3 and it will be seen from such figure that the matches are carried to the entrance chute 2 by means of a belt 41 driven by a drum 42. The drum is rigidly attached to a transverse shaft which also rigidly carries a sprocket wheel 43. This sprocket wheel is connected by means of a chain 44 with a similar sprocket wheel 45 rigidly associated with a bevel gear 46 (see Figures 2 and 3). The bevel gear 46 periodically meshes with the rotating milled gear 47, such latter gear being rigidly carried upon the lower end of the shaft 7.

It will be seen from this construction that the boxes 29 are fed in a step by step manner through the opening 28 in the sleeve 17. It is to be noted that the opening 28 within the sleeve 17 may have a rounded surface at the upper forward edge of such opening, as may be seen from Figure 3 so as to aid in forcing the matches downwardly into packed relation within the boxes 29.

The operation of the apparatus is as follows:—As the shafts 6, 7 and 8 rotate, the feed plunger 37 for the box covers 5 is reciprocated outwardly thereby pushing one box cover from the chute 4. This box cover is in front of the flexible nose of the plunger 19. Thereafter the sleeve 17 makes a forward stroke thus projecting its tapered resilient nose or end into the box cover and accurately aligning such cover. The plunger 19 then makes a forward reciprocation and feeds one of the filled boxes 29 forwardly into the cover.

It is to be noted from Figures 2 and 4 that although the boxes may be piled up with matches or over filled, it is, nevertheless, apparent that the extra supply of matches projecting above the box will have their butt ends engaged by the forward end of the member 31 of the plunger while the lower end of the plunger engages the rear face of the box. The plunger 19 presses the box forwardly and causes the matches to become relatively tightly packed within the boxes. This centering operation is diagrammatically illustrated in Figure 4 and it will be seen that the tapered resilient nose of the plunger 19 easily passes into the cover and accurately centers it. It will also be seen that the matches are pressed downwardly into the box and held in this pressed condition while the box is being inserted into the cover.

It will be seen that a cover filling machine has been provided in which three independent reciprocable members are provided for feeding the covers forwardly, for centering the covers and for projecting the filled boxes into the covers.

It will also be seen that this machine will rapidly and correctly fill the covers by inserting the filled boxes therein.

Although one form of the invention has been described in considerable detail, it is to be understood that the invention may be variously embodied and is, therefore, to be limited only as claimed.

It is to be further understood that although the matches have been shown with their heads pointing forwardly of the machine that obviously the matches may be arranged in the reverse manner, and further that although the machine is particularly adapted for the handling of safety matches, obviously, it may be used for other types of matches and for other articles.

15 I claim:

1. A machine for filling covers comprising a chute for said covers, a guideway adjacent said chute and adapted to receive covers from said chute, a reciprocatory sleeve adapted to reciprocate at right angles to said guideway and having a tapered nose adapted to enter a cover in said guideway and center it, a reciprocatory plunger mounted within said sleeve, 20 said sleeve having an opening through its side, means for sliding fillers through the opening in the side of said sleeve, means for reciprocating said sleeve, and means for reciprocating said plunger, whereby 25 said plunger will project a filler carried within said sleeve into the centered cover.

2. A machine for filling covers comprising a chute for supplying covers, a guideway adjacent said chute, means for moving a cover from said chute along said guideway, a reciprocatory sleeve adapted to reciprocate along a line crossing said guideway and having a flexible tapered nose adapted to enter a cover located within 35 said guideway and to thus center such cover, a plunger adapted to reciprocate through said sleeve, and means for putting fillers directly into said sleeve, whereby said plunger may project a filler through said sleeve 40 and into a centered cover.

3. A machine for filling match box covers comprising a chute for said covers, a guideway adjacent said chute, means for projecting a cover from said chute along said guideway, a sleeve adapted to reciprocate at right angles to said chute and having a tapering flexible nose adapted to project into a cover within said guideway to center said cover, a plunger adapted to reciprocate through said sleeve and through said flexible nose thereof, means for positioning filled boxes of matches in said sleeve, means for reciprocating said plunger, and means for reciprocating said sleeve to project said nose into a cover and retract said nose when said plunger approaches said cover.

4. A machine for filling match box covers comprising a bed plate, a plunger reciprocally mounted thereon, a shaft projecting through said bed plate and having a crank connected with said plunger, a sleeve surrounding said plunger and having a tapered nose, a second shaft projecting through said bed plate and having crank connection with 65 said sleeve, a guideway transversely arranged with reference to said bed plate, a reciprocatory member for advancing covers along said guideway, a third shaft projecting through said bed plate and having crank connection with said reciprocatory member, means positively connecting all three of said shafts and causing them to rotate in unison, and means for supplying boxes filled with matches to said plunger, 70 whereby the nose of said sleeve is reciprocated into and out of said covers while they are located within said guideway and said boxes are projected through said sleeve into said covers by said plunger.

5. A machine for filling match box covers comprising means for conducting said covers to said machine, a guideway located adjacent said means, a member adapted to project said covers from said supply means 80 along said guideway, a sleeve arranged at right angles to said guideway, means for supplying boxes filled with matches within said sleeve and a plunger adapted to reciprocate through said sleeve to project said 85 filled boxes into said covers, said plunger having an expansible forward end adapted to engage the upper and lower inner surfaces of said sleeve and said sleeve being tapered toward said guideway.

6. A machine for filling match box covers comprising means for conducting said covers to said machine, a guideway located adjacent said means, a member adapted to project said covers from said supply means 90 along said guideway, a sleeve arranged at right angles to said guideway, means for supplying boxes filled with matches within said sleeve, and a plunger adapted to reciprocate through said sleeve to project said 95 filled boxes into said covers, said plunger having an expansible forward end adapted to engage the upper and lower inner surfaces of said sleeve and said sleeve being tapered toward said guideway and having 100 a resilient nose, whereby said matches are pressed into said boxes as they are projected from said sleeve.

In testimony that I claim the foregoing I have hereunto set my hand at Marinette, 110 in the county of Marinette and State of Wisconsin.

ALPHONSE J. DE LEERS.
